UNITED STATES PATENT OFFICE.

AUGUSTUS S. CURRIER, OF HILLSBOROUGH, ILL., ASSIGNOR OF TWO-THIRDS
TO JOHN T. MADDUX AND GEORGE W. PAISLEY, OF SAME PLACE.

FIRE-ESCAPE.

SPECIFICATION forming part of Letters Patent No. 292,414, dated January 22, 1884.

Application filed April 19, 1883. (No model.)

To all whom it may concern:

Be it known that I, AUGUSTUS S. CURRIER, of Hillsborough, in the county of Montgomery and State of Illinois, have invented a certain 5 new and useful Improvement in Fire-Escapes, of which the following is a full, clear, and exact description, reference being had to the accompanying drawings, forming part of this specification, and in which—

10 Figure 1 is a front view; Fig. 2, a side view; Fig. 3, a view illustrating a manner of securing the rail or track to the building. Fig. 4 is an enlarged horizontal section taken on line 4 4, Fig. 2. Fig. 5 is a similar view taken 15 on line 5 5, same figure, looking upward.

My invention relates to that class of fire-escapes wherein a box or cage is made to move up and down the side of a building; and my invention consists in points of novelty here- 20 inafter fully described, and pointed out in the claims.

Referring to the drawings, A represents the side of a building, and B a "T-rail" secured thereto. The rail may be secured in any suitable 25 way; but I prefer to secure it, especially in stone and brick buildings, by means of plates C; built into the wall, (see Fig. 3,) having projections C', which fit holes in the rail, and riveted therein, as shown in said figure. 30 The plates may be placed suitable distances apart, as may be required, to hold the rail sufficiently secure.

D represents a box or cage, made of any suitable material and of any suitable construction, which is made fast to the rail (so as to be moved up and down thereon) by the following means:

E E represent arms made fast to the back of the box, and having their ends turned inward to engage the rear sides, B', of the head of the rail, as shown in Fig. 4. Extending downward and inward from the outer edge of the bottom of the box are arms F F and G G, the two latter of which have journaled 40 between their lower ends a friction-wheel, G', which bears upon the head of the rail, as

shown, and to the lower ends of the arms F are journaled friction-wheels F' F', which work on the web B'', and whose outer sides engage with the head of the rail, as shown. The car 50 or box is thus held to the rail and allowed to move freely up and down thereon. The arms F and G are connected by strengthening-braces I. (See bottom view, Fig. 5.)

J J represent rollers secured to the inner 55 lower corners of the box, which bear against the building to assist in guiding the box. They are journaled to inward-projecting arms J. (See Fig. 4.)

K represents a hoisting and lowering rope, 60 secured by one end to the box, and passing up over pulley or pulleys L, made fast at or near the top of the building, and from there down to the ground or pavement. The box may be raised and lowered by hand, or any other suitable power, and when not in use may be supported beneath the cornice of the building. A building may be supplied with any desired 65 number of them. I prefer to place them between a pair of windows, as shown.

The arms E may be duplicated, if desired. 70
I claim as my invention.—

1. In a fire-escape, the combination of T-rail B, secured to the structure, box D, having arms E, engaging the rear sides, B', of the 75 rail, lower arms, G, having roller G', running on the head of the rail, arms F, having rollers F', running on the web B'' of the rail behind the head, and a suitable hoisting-rope, as set forth.

2. In a fire-escape, the single rail or track B, made fast to the building by plates C, having necks or projections C', which are inserted in openings of the rail and riveted therein, in combination with the box D, connected to the 85 rail so as to be moved vertically thereon, substantially as set forth.

AUGUSTUS S. CURRIER.
